UNITED STATES PATENT OFFICE

99,400

DESIGN FOR A GLOVE

Charles R. Kovar, Richmond Hill, N. Y.

Application November 14, 1935, Serial No. 59,543

Term of patent 3½ years

To all whom it may concern:

Be it known that I, Charles R. Kovar, a citizen of the United States, residing at 102-32 Park Lane South, Richmond Hill, Long Island, in the city of New York, county of Queens, and State of New York, have invented a new, original, and ornamental Design for a Glove, of which the following is a specification, reference being had to the accompanying drawing, forming part thereof.

Figures 1 and 2 of the drawing are respectively front and back views of a glove showing my new design.

The entire exposed surface of the glove is covered with alternating series of short ridges, each

series extending transversely and being formed in the knitted fabric of which the glove is made. Each ridge of each series is disposed at an angle to the long axis of the glove except in the cuff portion on the back of the glove where the ridges of alternating series substantially coincide with the long axis of the glove and the ridges of the intervening series extend transversely. The design is further characterized by a strap formed of knotted cords.

I claim:

The ornamental design for a glove, as shown and described.

CHARLES R. KOVAR.
